UNITED STATES PATENT OFFICE.

JOE ROBINSON, OF MATTEAWAN, NEW YORK.

KEYHOLE-GUIDE.

1,110,963.

Specification of Letters Patent. Patented Sept. 15, 1914.

Application filed December 17, 1913. Serial No. 207,280.

To all whom it may concern:

Be it known that I, JOE ROBINSON, citizen of the United States, residing at Matteawan, in the county of Dutchess and State of New York, have invented certain new and useful Improvements in Keyhole-Guides, of which the following is a specification.

The present invention aims to provide new and useful improvements in face plates or escutcheons for door locks, and has particular reference to that type of such devices which are formed in the nature of key-hole guides.

As the principal object, therefore, the present invention aims to provide an ornamental face plate or escutcheon for door locks, forming the device in such a manner that it will serve as a guide when the key is applied to the lock.

A further object is to construct the guide plate with such regard to the proportion and number of parts that it may be cheaply manufactured, will be durable and efficient in its action, and may be readily applied to any ordinary form of lock.

The above and additional objects are accomplished by such means as are illustrated in the accompanying drawings, described in the following specification, and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts, Figure 1 is a perspective view of the preferred form of key-hole guide plate illustrating the device in disassembled position with the pivot closure plate in open position; Fig. 2 is a detailed perspective view illustrating a modified form of the device in assembled relation; Fig. 3 is a sectional view illustrating the modification of Fig. 2 in assembled position on a lock; Fig. 4 is a detailed perspective view illustrating a further modification of the device.

Proceeding now to the description of the invention and referring particularly to Fig. 1, the preferred embodiment of this invention consists essentially in a body plate 10 which, as shown, is substantially rectangular in shape. This body member 10 may be

either cast or formed from pressed metal in the well-known manner. The body plate 10 is formed in the nature of a shell which is frusto-pyramidal in shape, the object in thus forming the body member being to provide the four inwardly converging walls 11, 12, 13, and 14. It will be noted that the shell or body plate is formed with a key-hole opening 15 which lies at the inner portion of the shell. Formed on the outer edges 65 of the walls 13 and 14, which constitute the upper and lower walls of the shell, are a pair of spacing lips or walls 16 and 17 which extend at right angles to the plane of the outer edges of the walls 11, 12, 13, and 14 70 and are bent outwardly and at right angles at their free ends to produce the apertured attaching portions 18 and 19. The member 18 is formed centrally on the member 17, while the member 19 extends the entire 75 length of the member 17, as will be readily observed upon reference to Fig. 1. Upon reference to this figure also, it will be further noted that the lower edges of the members 16 and 17 lie in the plane of the inner 80 edges of the walls 11, 12, 13, and 14, being thus adapted to properly support the body portion or shell 10 against the face of the door. Screws, rivets, or other suitable fastening devices, may be applied to the 85 attaching portions 18 and 19 for holding the device in the desired position on the door.

As a means for normally sealing the key-hole opening 15 to prevent the exposure of 90 the lock to the rain, hail, and the like, there has been provided a pivot closure plate 20 which, as shown, is preferably rectangular in shape and formed from sheet brass, copper, or any other desired metal, which is possessed of ornamental and decorative properties. On the upper end of the plate 20 is formed a lug 21 which is provided with a longitudinally extending bore through which is inserted a pivot pin 22. In this connection, it may be observed that, if found desirable, the pivot pin 22 may be also employed as the means for securing the member 18 to the door. A finger-piece 23 may be secured to the closure plate 20 for the obvious purpose of enabling the operator to swing the closure plate upwardly on its pivot pin so that access may be had to the key-hole. 100 In the modification illustrated in Fig. 2, it will be noted that the key-hole guide plate 110

is substantially similar to the body portion or shell 10 of the preferred form, above described. Inasmuch as the modification of Fig. 2 is designed to be embedded in the face 5 of the door, as will be noted upon reference to Fig. 3, the members 16, 17, 18, and 19, and the closure plate 20 have, of course, been omitted. It will thus be noted that the modification illustrated in Fig. 2 consists 10 merely in a frusto-pyramidal shell which is modified for the receiving recess formed in the face of the door and operates in the same manner as the preferred form of the device to properly guide the key into the key-hole. 15 The modification illustrated in Fig. 4 is also greatly similar to the preferred form, with the exception that the attaching portions 18 and 19 of the preferred form are elongated to provide plates 25 and 26. These 20 plates 25 and 26 render a more ornamental appearance to the device, inasmuch as they may be embossed with the family coat of arms or an appropriate design. When the modification illustrated in Fig. 4 is employed, the member 25 is formed with an opening 27 through which the stem of the door-knob may be directed. 25

Concluding the description of the invention, it is desired to direct particular attention to the fact that the key-hole guide plate 30 is extremely simple in construction, is so formed that it will be durable and highly efficient in its action, and is so designed that it will lend an ornamental appearance rather 35 than detract from the appearance of the door. In reduction to practice, I have found that the form of my invention, illustrated in the drawings and referred to in the above de-

scription, as the preferred embodiment, is the most efficient and practical; yet realizing 40 that the conditions concurrent with the adoption of my device will necessarily vary, I desire to emphasize the fact that various minor changes in details of construction, proportion and arrangement of parts may be 45 resorted to, when required, without sacrificing any of the advantages of my invention, as defined in the appended claim.

What I claim is:—

The combination with a lock, of a key-hole guide consisting of a frusto-pyramidal shell having a key-hole at its smaller terminal, the shell being arranged in registration with the key-hole of the lock, end walls formed at the upper and lower edges of the 55 body member and extending at right angles to the plane of the outer edges of the body member and in the direction of the lock, apertured portions extending outwardly at right angles to the end walls for securing the 60 body member to the supporting surface, a lug extending laterally from one apertured portion and in parallel spaced relation to the adjacent end wall, said lug being provided with a longitudinal bore, a pivot pin 65 extending through the bore, and a closure plate having its upper terminal pivoted on the outer terminal of the said pin and bearing against the outer terminal of the said lug.

In testimony whereof I affix my signature in presence of two witnesses.

JOE ROBINSON. [L. s.]
